UNITED STATES PATENT OFFICE.

HARRY BUXTON HARTMAN, OF SCOTTDALE, PENNSYLVANIA.

SAFETY-RAZOR STROP.

Application filed June 14, 1923. Serial No. 645,390.

To all whom it may concern:

Be it known that I, HARRY BUXTON HARTMAN, citizen of the United States, residing at Scottdale, in the county of Westmoreland 5 and State of Pennsylvania, have invented certain new and useful Improvements in Safety-Razor Strops, of which the following is a specification.

This invention relates to an improvement 10 in razor stropping devices, and more particularly to a strop adapted for sharpening the blades used in safety razors.

To that end the invention contemplates a safety-razor blade-strop for sharpening both edges of double edged blades or if desired to also sharpen single edged blades. In many of the stroppers now in general use the blades are oscillated into engagement with the reciprocating strop and the oscillatory movement of the blade is brought about by a pressure exerted against the inner or stropping face of the strop, and this action has a tendency to greatly injure the stropping face. Furthermore, in these commercial stroppers, the blades are not always started in their oscillatory movement until after the strop has begun its movement of reciprocation and inasmuch as the movement of the strop is against the cutting edge 20 of the blade, the strop is very often injured by said blade.

One of the principal objects of the present invention is to provide a strop which is capable of sharpening either a double edged 30 or a single edged safety razor blade with ease and facility.

Another object of the invention is to provide a strop for sharpening both edges of a double edged safety razor blade without 40 reversing or without removing the blade.

A further object is to provide a tensioning device for the strop which engages the outer face thereof so as to avoid injury to the inner face of the strop.

A still further object is to provide means for causing the blade to begin its movement of oscillation prior to the strop beginning its major movement of reciprocation whereby all danger of the strop being cut by the 50 blade will be prevented.

With these and other objects in view which will more readily appear as the nature of the invention is better understood, the same con-

sists in the novel construction, combination and arrangement of parts hereinafter more 55 fully described, illustrated and claimed.

In the drawings:

Figure 1 shows a front elevation of a strop embodying my invention.

Figure 2 is a side elevation thereof. 60

Figure 3 is a vertical sectional view taken on the line 3—3 of Figure 1.

Figure 4 is a horizontal sectional view taken on the line 4—4 of Figure 1.

Figure 5 is a vertical sectional view 65 through the strop, showing a double edged blade supported thereon.

Figure 6 is a vertical sectional view taken on the line 6—6 of Figure 5.

Figure 7 is a detail horizontal sectional 70 view taken on the line 7—7 of Figure 5.

Figure 8 is a detail elevation showing a single edged blade and holder therefor, and

Figure 9 is an end elevation thereof.

Like reference numerals designate corresponding parts throughout the several figures of the drawings.

In carrying out my invention, I provide a main frame A which I preferably stamp from a single blank of sheet metal and bend 80 into a U-shaped formation to provide spaced parallel legs 5 and 6 respectively, and a connecting portion 7, the latter being stamped with depending side flanges 8—8. Journaled in the legs 5 and 6 is a razor blade carrier which I have designated as a whole by the reference letter B, this carrier being journaled in bearings 9 and 10 which are respectively formed in the legs 5 and 6. 85

The carrier B is preferably formed from an elongated strip of sheet metal which is re-bent as at 11 to form spaced parallel walls 12—12, the free end portions of the walls 12 being curved to conjointly form a journal 13 engageable with the bearing 10 in the leg 6 of the main frame. The re-bent end portion 11 of the carrier is frictionally engaged with an angular opening 14 formed in a bearing sleeve 15, engageable in the bearing 9 of the leg 5 of the main frame. This bearing sleeve 15 is formed with peripheral flanges 16 and 17 which are respectively disposed on opposite sides of the leg 6. These flanges, therefore, serve to retain the bearing sleeve 15 against lateral movement. The inner flange 17 is formed with a toothed segment 100 105

18 which extends upwardly towards the connecting portion 7 of the frame for the purpose hereinafter described. The walls 12-12 of the carrier are each formed with 5 upper and lower inwardly offset and longitudinally extending razor blade gripping jaws 19 and 20.

Journaled in the legs of the main frame above the carrier B is a roller bearing for 10 the strop C. This roller bearing consists in a rod 21 fixed to said legs and a bearing sleeve or roller 22 which is loosely journaled on said rod and over which the strop C is re-bent.

15 In order to oscillate the carrier B by reciprocatory movements of the strop, I have provided a rocking frame which I have indicated as a whole by the reference character D. This rocking frame is preferably 20 formed of sheet metal and is stamped into a U-shaped form consisting of spaced legs 23 and 24 respectively and a connecting portion 25, the said legs being journaled on the rod 21 and the connecting portion 25 being

25 disposed between said rod 21 and the connecting portion 7 of the main frame, the legs 23 and 24 embracing the strop C. The lower extremity of the leg 23 is provided with a toothed segment 26 which engages

30 the segment 18 of the carrier B. Thus when the frame D is rocked about its fulcrum upon reciprocatory movements of the strop, the razor blade carrier B will be rocked in the opposite direction. The end portion of 35 the strop C extends downwardly on opposite sides of the razor blade carrier and on the opposite sides of the spacing bar 27 which is secured to the lower end of said main frame.

40 The segmental rack 18 of the carrier is disposed in an arc struck from the axis of the carrier and the segmental rack 26 is disposed in an arc struck from the axis of the rocking frame. The radius of the segmental rack 18 is considerably less than the radius of the rack 26. Consequently the 45 slightest oscillation of the rocking frame will multiply the rocking movement of the carrier B.

45 In order to oscillate the rocking frame D upon reciprocatory movement of the strop C, I provide a tensioning device for said strop. This tensioning device consists of a pressure plate 28 which is disposed above the bearing roller or sleeve 22 and the re-

50 bent portion of the strop is disposed between the said bearing plate and said roller. The opposite ends of the pressure plate are formed with guiding tongues 29-29 which have free sliding movements in vertically 55 extending slots 30-30 formed in the legs 23 and 24 of the rocking frame so as to retain said plate against lateral movements relative to said frame but to permit vertical movements relative thereto. In order to 60 exert a predetermined pressure upon the

outer face of the strop by said plate I have provided an upwardly bowed flat spring 31, the ends thereof having slidable engagements on the end portions of said pressure plate. The end portions of the spring 31 are 70 disposed between spaced lugs 32-32 and 33-33 respectively, said lugs being preferably stamped from the pressure plate and serve to retain the spring 31 against accidental displacement. In order to vary the 75 amount of pressure by the spring 31, I have provided an adjusting screw 34 which consists of a threaded shank 35 and a knurled head 36. The knurled head is disposed between the spring 31 and the connecting portion 25 of the rocking frame D, and the shank has threaded engagement with said connecting portion 25. The diameter of the head 36 is greater than the width of the connecting portion 25 so as to extend beyond 80 the side edges thereof and thereby permit said head to be readily engaged by the fingers.

85 In order to provide means for supporting either a double edged blade or a single edged blade within the carrier B, I have provided blade holders E and F respectively. The holder E is formed from a flat piece of metal and extending from one face thereof is a plurality of studs 37-37 for supporting a double edged blade 38, said blade having openings 39-39 for receiving the studs 37. The holder F is likewise formed from flat metal and includes spaced resilient clamping arms 40-40 adapted to receive and frictionally engage the butt edge portion of a single edged razor blade 41. The holders E and F are adapted to be positioned in the carrier between the spaced walls 12-12 thereof. An insertion is made through an 90 elongated opening 42 formed in the leg 6 of the main frame A. This opening extends above and below the bearing 10 and the lower portion of said opening 42 is of a greater length than the upper portion thereof so as to permit the single edged blade 41 being readily inserted within the carrier. It is to be noted that when the holder E and the double edged blade 38 is inserted, said 95 blade will be frictionally gripped by the gripping jaws 19 and 20 of the carrier. When, however, the holder F and the single edged blade 41 is inserted the gripping jaws 20 only engage the blade.

100 In order to attach the stropper to any suitable support I have provided the main frame A with a swivel ring 43, said ring being swiveled in the connecting portion 7 of the frame.

105 From the foregoing, it will be observed that when sufficient pressure is exerted against the strop through the medium of the spring 31, a resistance to the reciprocatory movement of the strop relative to the rocking frame will be created. Consequently 110

the rocking frame will be oscillated prior to the strop being reciprocated relative to said rocking frame. Inasmuch as the rocking movement of the carrier is multiplied by the segmental rack connections with the rocking frame, the initial movement of the strop will cause the blade to be quickly withdrawn from its engagement with the strop and as a result the blade will not cut 5 or otherwise injure said strop.

It will be also observed that I have provided a stropper which is adapted to sharpen either a double edged or a single edged safety razor blade; that both edges of the 15 double edged blade will be sharpened without the necessity of either reversing or removing the blade; that the tensioning device for the strop engages the outer face thereof and consequently the inner or sharpening 20 face of the strop will not be injured thereby, and that the oscillatory movement of the blade is begun prior to the major reciprocatory movement of the strop and consequently the blade is withdrawn from the 25 strop and the latter will not be injured or cut by said blade. When the blade is rocked into engagement with the inside face of the strop C by manipulating the strop, it will be seen that the walls or plates 45 which 30 connect the legs 5 and 6 form abutments against which the strop bears to limit the amplitude of oscillation of the blade and also insure firm contact between the blade edge and the strop.

Without further description it is thought that the features and advantages of the invention will be readily apparent to those skilled in the art, and it will, of course, be understood that changes in the form, proportion and minor details of construction may be resorted to, without departing from the spirit of the invention and scope of the appended claims.

I claim:

1. A razor blade stropper including a main frame consisting of top and side members, a rockable frame also consisting of top and side members and fitting within said main frame, a member pivotally connecting the main and rockable frames and holding the same in assembled relation, means on the main frame for supporting a razor blade holder and operatively connected with the rockable frame, a strop passing over the member for pivotally connecting said frames, and a tensioning device carried by the rockable frame and having a part for engaging the strop.

2. A razor blade stropper including a main frame consisting of top and side members and a rockable frame also consisting of top and side members journaled on the main frame at the inside thereof and provided with a bearing rod, a strop doubled over said rod, a razor blade carrier disposed be-

tween and journaled in the side members of the said main frame, means connecting the rockable frame and the blade carrier for rocking the latter upon the movement of the rockable frame, and tensioning means 70 carried by the rockable frame and cooperating with the bearing rod and the outer face of the strop whereby the movement of the latter actuates the frame.

3. In a razor blade stropper, the combination with a main frame, of a rockable frame journaled on the main frame and provided with a bearing rod, a strop re-bent over said rod, a razor blade carrier disposed between the end portions of the strop and journaled 80 on said main frame, means connecting the rockable frame and the carrier for rocking the latter upon rocking movements of the former, and a pressure plate disposed above the bearing rod and co-operating with the outer face of the strop, and means for varying the pressure of the plate against the strop.

4. In a razor blade stropper, the combination with a main frame, including a bearing rod, of a strop re-bent over said rod, a rockable frame including spaced legs and a connecting portion, the legs embracing the strop and being fulcrumed on said rod, a razor blade carrier disposed between the end portions of the strop and journaled on the main frame below the rockable frame, means whereby the rockable frame engages said blade carrier to oscillate the same, a pressure plate disposed above the bearing 90 rod and co-operating with the outer face of the strop, a bowed spring interposed between the connecting portion of the rockable frame and the pressure plate, and an adjusting screw interposed between said connecting portion and the spring for varying the tension of the latter.

5. In a razor blade stropper, the combination with a main frame, including a bearing rod, of a strop re-bent over said rod, a rockable frame including spaced legs and a connecting portion, the legs embracing the strop and being fulcrumed on said rod, a razor blade carrier disposed between the end portions of the strop and journaled on the main frame below the rockable frame, means whereby the rockable frame engages said blade carrier to oscillate the same, a pressure plate disposed above the bearing 100 rod and co-operating with the outer face of the strop, a bowed spring interposed between the connecting portion of the rockable frame and the pressure plate, said plate being provided with upwardly extending lugs to retain the spring in co-operative relation with said plate, and means for varying the tension of said spring.

In testimony whereof I hereunto affix my signature.

HARRY BUXTON HARTMAN.
